UNITED STATES PATENT OFFICE.

CHARLES B. KING, OF DETROIT, MICHIGAN.

RHEOSTAT SOCKET.

Application filed April 13, 1922. Serial No. 552,185.

To all whom it may concern:

Be it known that I, CHARLES B. KING, a citizen of the United States, and resident of Detroit, county of Wayne, State of Michigan, have invented certain new and useful improvements in Rheostat Sockets, of which the following is a specification.

This invention relates to a rheostat socket of a type particularly adapted to be used in connection with radio apparatus.

An important object of the invention is to provide a simple, effective and compact device of the character mentioned by which the customary amplifying or detector tube used in connection with the radio apparatus may be combined with a rheostat adapted to control or vary the amount of current passed through the same.

A further object of the invention is to generally improve the rheostat mounting and assembly, and so construct the device that certain electrical units, such as amplifying transformers may be mounted thereon and form a complete amplifying unit or that a condenser and grid leak may be mounted thereon thus forming a detector unit.

Other objects and certain advantages of the invention will become apparent from the following description when taken in connection with the accompanying drawings in which:

Figure 1 is a side elevation of the device embodying my invention.

Figure 2 is a transverse sectional view taken on line 2—2 of Figure 1.

Figure 3 is a rear view of the device as seen from the left in Figure 1.

Figure 4 is a top plan view of the device, the amplifying tube being removed therefrom.

Figure 5 is a sectional view taken on line 5—5 of Figure 4.

In the drawings wherein is shown what I at present consider the preferred form of my invention, the numeral 5 indicates a panel having peak holes 6 provided therein through which the amplifying or detector tube, hereinafter more particularly referred to may be viewed. At the rear of the board 5 there is provided a socket indicated as a whole by the numeral 7. This socket is preferably constructed from suitable insulating material and comprises a base 8, from which is extended a sleeve 9, adapted to receive the socket portion 10, of the usual form of tube

11. In order that the tube 11 may be temporarily locked within the socket 9 there is provided a bayonet shaped slot 12 into which a lug 13, carried by the socket portion 10 of the tube is adapted to fit. The base 8 is cut away directly beneath the socket 9 to provide a cavity or chamber 14 into which the usual filament plate and grid terminals are adapted to project when the tube 11 is locked within the socket 9. A pair of webs 15 are formed integral with the base 8 and the socket 9. These gussets are spaced an appreciable distance from each other and present curved surfaces 16 at their inner sides thus forming a rheostat pocket 17 intermediate the panel 5 and the socket 9. Within the pocket 17 there is arranged an arcuate shaped rheostat 18 which comprises a core of insulating material 19 around which is wound a resistance wire 20. In order to effectively retain the rheostat 18 in position there is provided a locking block 21 which is cut away as shown at 22 in order that the same may be spaced an appreciable distance from the base 8, as most clearly shown in Figures 2 and 5. This block is provided centrally with a socket 23 into which is fitted one end of an operating shaft 24 which, at its outer end, is provided with a knob 25 suitably locked thereto as by means of a set screw 26. The operating shaft carries a conductor finger 27 bent at its outer end to provide a contact foot 28 adapted to engage the rheostat 18 at any desired location. The shaft 24 is retained normally within the socket 23 by means of a resilient conductor 29 one end of which is extended to engage one of the filament contacts, whereas the other end is bent to provide a resilient arm 30 having a contact foot 31 which is maintained in thrusting engagement with the contact arm 27. It will be appreciated that by the inherent resilience of the arm 30 the shaft 24 will be retained within the socket 23, and the contact arm 27 will be retained in intimate engagement with the rheostat 18. The conductor 29 is secured in position by means of an elongated screw 32 which also serves to retain the locking block 21 in proper position within the rheostat 18. It is apparent that the locking block 21 and the screw 32 affords a simple and effective means for rigidly locking the rheostat 18 within the pocket 17 for the reason that when the screw 32 is adjusted

to move the block 21 downwardly an impinging action of the same is exerted upon the rheostat 18 thereby clamping the same between the wings or gussets 15 and said block.

5 Not only does this locking means make possible easy assembling of the device but also enables the several associated elements to be quickly disassembled if it should be desired for example to replace certain elements of

10 the device.

To the under side of the base 8 there is connected a filament contact arm 33, a grid contact arm 34 and a plate contact arm 35. These contact arms are held in position by

15 means of screws 36 adapted to engage internally screw threaded bosses 37 carried upon the opposite side of the base 8. These bosses are provided with binding screws 38 by means of which suitable conductors are

20 electrically connected with the filament, grid, and plate contact arms 33, 34 and 35 respectively. Within the base 8 there is moulded an internally screw threaded sleeve 39 which is adapted to receive a screw 40 the inner

25 end of which is maintained in engagement with the rheostat 18. The sleeve 39 is also provided with a binding screw 41 by means of which a suitable conductor leading to the rheostat is electrically connected to the

30 sleeve.

It might be remarked that under certain conditions it would be desirable to mount on the socket 7 certain electrical units such for example as an amplifying transformer 41 thus forming an amplifying unit or if a detector unit by the mounting of a condenser and grid leak thereon and to this end I have illustrated, as shown at 42, a pair of internally screw threaded sleeves which are

35 adapted to be moulded into the material from which the socket is formed. While I have shown only two of these sleeves it is to be understood that as many may be moulded in the device as are deemed necessary to

40 accommodate such electrical units as it may be desired to associate with the device embodying my invention. It will be noted that the gussets 9 are also provided with internally screw threaded sleeves which are

45 moulded therein as shown at 43. These sleeves are adapted to receive screws 44 by which the device may be attached to a panel such as is indicated by the numeral 5. If the device is to be attached to a base or other

50 support, the screw holes 45 formed in the base 8 may be employed for the reception of screws or bolts for rigidly mounting the device.

It will be understood that by turning the

55 shaft 24 in one direction or the other through the instrumentality of the knob 25, the position of the contact arm 27 may be so changed as to cut out or set in more or less resistance between the source of electrical energy and the filament of the tube of the

amplifying or detector unit. It will be appreciated that while the position of the arm 27 is being changed and after the same has been set at a desired position an intimate contact is afforded between the arm and the rheostat 18 and also between the arm and the conductor 30 by reason of the inherent resiliency of the latter named element which tends to exert an end thrust upon the shaft 24 at all times. It will be also appreciated that, by reason of the resiliency of the contact arms 33, 34 and 35, a positive electrical connection between the filament, plate, and grid terminals and their respective contact arms is afforded at all times. To limit the movement of the contact arms 27 in one direction I have provided a stop 46 which is formed integral with the block 21 and positioned relatively near one end of the rheostat 18. When the contact arm 27 is moved in an opposite direction it is desirable to relieve engagement of the same with the rheostat 18 after the same has reached or nearly reached the limit of its travel, and to this end I provide a cam 27 which is also carried by the block 21.

Having thus described my invention I claim:

1. A rheostat socket comprising a base adapted to receive a tube, a rheostat element combined therewith for varying the amount of current supplied to said tube, and a movable clamping element adapted to lock said rheostat element in place.

2. A rheostat socket comprising a base adapted to receive a tube, a rheostat element associated with said base for varying the amount of current supplied to said tube, a locking means located within said rheostat and adapted to lock the same in place, an operating shaft, and a contact arm carried by said shaft and adapted to engage said rheostat element.

3. A rheostat socket comprising a base adapted to receive a tube, a rheostat element associated with said base for varying the amount of current supplied to said tube, a clamp adapted to lock said rheostat element in place, an operating shaft, a contact arm carried by said shaft and adapted to engage said rheostat element, and resilient means adapted to urge said arm into intimate electrical engagement with said rheostat element.

4. A rheostat socket comprising a base adapted to receive a tube, a rheostat element associated with said base for varying the amount of current supplied to said tube, a clamping block adapted to lock said rheostat element in place, a rotatable and longitudinally movable operating shaft associated with said block, a contact arm carried by said shaft and adapted to engage said rheostat element, and a resilient conductor engaging said arm, said conductor being

adapted to urge said arm into intimate electrical engagement with said rheostat.

5. A rheostat socket comprising a base adapted to receive a tube, said base being provided with a rheostat pocket having walls, a rheostat coil arranged within said pocket, a binding block arranged within said coil, and means for moving said block to effect an impinging action upon said coil whereby the same is retained within said pocket.

6. A rheostat socket comprising a base adapted to receive a tube, said base being provided with a rheostat pocket having walls, a rheostat element arranged within said pocket, a binding block arranged within said pocket, means for moving said block to effect an impinging action upon said element whereby the same is retained within said pocket, an operating shaft, and a contact arm carried by said shaft and adapted to engage said element.

7. A rheostat socket comprising a base adapted to receive a tube, said base being provided with a rheostat pocket having walls, a rheostat element arranged within said pocket, a binding block arranged within said coil, means for moving said block to effect an impinging action upon said coil whereby the same is retained within said pocket, an operating shaft, a contact arm carried by said shaft and adapted to engage said element, and a resilient conductor adapted to exert an end thrust upon said shaft whereby said arm is urged into contact with said element.

8. A rheostat socket comprising a base adapted to receive a tube, a rheostat element associated with said base for varying the amount of current supplied to said tube, means adapted to lock said rheostat in place, an operating shaft, a contact arm carried by said shaft and adapted to engage said rheostat element, and means for releasing the engagement of said arm with said rheostat element after a predetermined movement of said arm over said element.

9. A rheostat socket comprising a base adapted to receive the contact end of a tube having exposed filament, plate and grid terminals, a rheostat element associated

with said base, a locking block arranged within said element, means for adjusting said block to exert an impinging action upon said coil whereby the same is retained in position, an operating shaft, a contact arm carried by said shaft and adapted to be moved to different positions upon said element to vary the amount of current supplied to said tube, resilient conductors adapted to engage said filament, plate, and grid terminals, one of said conductors being maintained in electrical engagement with said arm whereby said arm is urged into intimate electrical engagement with said element.

10. A rheostat socket comprising a base adapted to receive a tube having exposed filament, grid and plate terminals, a rheostat element associated with said base, an operable contact arm for said rheostat element, a conductor leading to one of said terminals, said conductor being resilient and adapted to cooperate with said contact arm to urge the same into intimate electrical engagement with said rheostat element.

11. A rheostat socket comprising a base adapted to receive a tube, a rheostat element associated with said base, an operating shaft, a contact arm carried by said shaft and adapted to engage said rheostat element, and a resilient conductor adapted to exert an end thrust upon said shaft whereby said arm is urged into contact with said element.

12. A rheostat socket comprising a base adapted to receive the contact end of a tube having exposed filament, plate and grid terminals, a rheostat element associated with said base, an operating shaft, a contact arm carried by said shaft and adapted to be moved to different positions upon said rheostat element to vary the amount of current supplied to said tube, conductors adapted to engage said filament, plate and grid terminals, one of said conductors being maintained in electrical engagement with said arm.

In testimony whereof, I have affixed my signature to this specification.

CHARLES B. KING.
